CIGARETTE ROLLING FORM

Arthur H. Hood, Jr., Philadelphia, Pa., assignor
to Max N. Carol, as trustee

Application March 17, 1942, Serial No. 434,997

2 Claims. (Cl. 131—58)

This invention relates to cigarette rolling forms.

Various metal and other devices have been made and sold to assist an individual in rolling or forming his own cigarettes, using a special paper wrapper, sold for the purpose. Such devices are comparatively expensive and are not handy to carry around for use, when needed.

It is therefore one of the objects of my invention to provide a simple cigarette rolling form, that can easily be carried in one's pocket, having the said form made of suitable, semi-stiff, sheet material, which is preferably somewhat elastic and which can be easily bent to the same radius of curvature as that of a cigarette, without cracking at its curved outer surface.

Another object is to provide a sheet, cigarette rolling form, which, while fulfilling the above named object, will be preferably narrower than a regular size of cigarette paper wrapper, so that when rolling a cigarette within the form, a longitudinal edge of the wrapper, can come next to and outside of the outer longitudinal edge of the form, when said form is rolled, exposing said longitudinal wrapper edge.

A further object is to have one or both ends of said form tapered, and at the same time have the form a little longer, from end to end, than the length of the cigarette wrapper, so that when a cigarette is rolled within the form, and is still coiled about the formed cigarette, there will be a greater exposure of the cigarette wrapper where the inclined edge of the tapered end of the form recedes from the edge of the wrapper, enabling the one rolling the cigarette, to contact a greater area of the cigarette and thus get a better frictional hold thereon, to withdraw the same from the still coiled form. The tapered end of the coiled form, extending beyond the cigarette within, becomes stiff, when curved, so that when the formed cigarette is gripped, the stiff, curved, blunt, point of the tapered end of the form, will resist flat crushing of the cigarette end when it is gripped.

With these and other objects, which will hereinafter appear, my invention resides in certain construction of a guiding sheet form adapted for rolling a cigarette, one embodiment of which form is illustrated in the accompanying drawing, its construction is described, its use is explained, and what I claim is set forth.

In the drawing,

Figure 1 is a plan of an ordinary cigarette paper wrapper.

Figure 2 is a plan of the cigarette rolling form embodying my invention.

Figure 3 is a top plan of the said form having the cigarette wrapper superimposed, in initial position thereon.

Figure 4 is an edge view of the cigarette paper wrapper as laid upon a curved rolling form.

Figure 5 is a perspective view of the cigarette wrapper and accompanying form, held in trough formation, with tobacco laid therein.

Figure 6 is a top plan of the formed cigarette coiled within the form.

Figure 7 is an enlarged end view of the cigarette, within the coiled form as shown in Figure 6.

In the figures, 10 is the cigarette rolling form, preferably made of suitable elastic and semi-stiff, sheet paper material of a thickness that can easily be coiled, without cracking at the convex surface. The form 10 is shown to have a long base line or upper edge 11, and tapered ends 12 and 13. As shown in Figure 2, the tapered ends 12 and 13 each terminates in a short line 22, substantially parallel to the base line 11, so that the tapered ends are preferably blunt and of a width adapting either end to afford a curved support to the contacting end of the cigarette, while this end is exposed above to be gripped. No particular outlined formation of the side lines 15 and 16, of the tapered ends is required. Any formation of tapered end, other than that shown in full lines can be used, if the shape thereof, when rolling a cigarette, leaves exposed a definite area, at an adjoining end of the rolled-in cigarette wrapper 17, as at 18 or 19, for a practical, frictional grip, when one is about to withdraw the cigarette from the coiled form. As shown, the inclined or sloping lines 15 and 16, of the tapered ends 12 and 13, respectively, merge into the short line 22, which preferably is approximately parallel with the base line 11. While only one tapered end of the form is needed at a time, the tapering of both ends affords a choice of ends, when the form is used.

In operation, the user takes a cigarette paper wrapper, as 17, which is shown to have a gummed edge 23, although a wrapper without a gummed edge may be used, and places the wrapper 17 upon the form 10, and in the case of one with a gummed edge 23, this edge is held uppermost and relatively positioned upon the form 10, as shown in Figure 3, with the long edge 11, of the form 10, spaced below the gummed edge 23, of the wrapper 17. Next, he holds these pieces horizontal, with the wrapper on top of the form,

and with the short edge 22, toward him, then while still holding the pieces horizontal, he distributes tobacco 24, along the mid-line, of the wrapper 17, and turns up the sides to form a trough 20, as shown in Figure 5, with the tobacco 24 in the bottom of the trough with the form 10 on the outside and the wrapper 17 between the tobacco 24 and the form 10. He then slightly rolls the trough portion, of the form 10 between the fingers and thumbs, to better consolidate the tobacco into a denser cylinder, after which, he turns the wrapper portion, which is next to the short edge 22, away from him and down upon the tobacco 24, and rolls it and the edge 22 in, and continues the rolling until he brings the gummed surface 23 (when a gummed edged wrapper is used) down toward himself, on top of the coiled form 10, as shown in Figure 6. After this is done, while still holding the form 10 in coiled formation, he slightly releases his grip on the coil, and with one hand holding the coil, he places a finger or thumb, (of the other hand), on one end of the formed cigarette, as at 18, and taking hold, pulls the cigarette partly out of the coiled form 10 to some such position as shown by the dotted outline 26, and before pulling the cigarette out further, he moistens the end of the gummed edge 23, or a similar end of an un-gummed wrapper, and sticks it down onto the body of the wrapper 17, then pulls the cigarette free from the form 10, after which he further moistens and finishes the sticking down of the edge 23 and, after fully withdrawing the formed cigarette, he, while holding the same rolled, moistens the full length of the edge 23 and sticks it all down from end to end, of the cigarette.

After thus forming the cigarette, any project-

ing tobacco can be cut off by shears, close to the rolled wrapper ends.

By initially curving the form 10, as shown in Figure 4, the rolling operation, in making the first cigarette, is facilitated, however, after the first few cigarettes are made with form 10, it becomes permanently curved a little. The form 10 is preferably made from some suitable sheet material, as paper or some other stock that is somewhat elastic, so that when not held coiled, it will return to a slightly curved formation.

While I have shown and described one embodiment of my invention, modifications thereof can be made without departing from the spirit of my invention. I therefore wish to include all forms which come within the scope of the following claims.

I claim:

1. A form adapted for rolling a cigarette, said form consisting of a sheet body made of semi-stiff, elastic rollable material, and a tapered end to said body, adapted, when holding a cigarette, its wrapper and tobacco rolled within said form, to expose part of a wrapper end of said cigarette for withdrawal purposes.

2. A sheet form adapted for rolling a cigarette wrapper around a line of tobacco contained thereon, said form having a tapered end, said form being a little longer than said wrapper, thereby affording curved and strengthening support to the rolled-in cigarette end adjoining the tapered end of said form, and at the same time, the sloping, rolled edge of the tapered end receding from the end of the rolled-in wrapper, exposing part of said wrapper end for gripping and withdrawal purposes.
